UNITED STATES PATENT OFFICE.

WILLIAM BARTHOLOMEW, OF CHICAGO, ILLINOIS, ASSIGNOR TO TROY LAUNDRY MACHINERY CO., LTD., OF CHICAGO, ILLINOIS, A CORPORATION OF NEW YORK.

CENTRIFUGAL MACHINE.

1,425,628.

Specification of Letters Patent. Patented Aug. 15, 1922.

Application filed September 15, 1920. Serial No. 410,432.

To all whom it may concern:

Be it known that I, WILLIAM BARTHOLOMEW, a citizen of the United States, residing at Chicago, in the county of Cook and State 5 of Illinois, have invented certain new and useful Improvements in Centrifugal Machines, of which the following is a specification.

The present invention relates to centrifugal machines, and particularly to the connection between the rotary spindle and the basket or receptacle which is mounted thereon to be driven thereby.

It has been the practice to connect the upper end of the rotary cylinder in a centrifugal machine with the receptacle, for instance, the basket of a centrifugal extractor used for laundry purposes, by fitting the hub of the receptacle (generally a cast metal member) directly upon the end of the spindle through the medium of a tapered fit, driving connection being usually established through friction developed by forcing the hub tightly upon its tapered seat. But sand 25 or grit from sand holes or blow holes in the casting, released by machining the bore, has sometimes found its way to the meeting surfaces of the hub and spindle which causes injury to the spindle and interferes with pulling the two members apart when it becomes necessary to remove the basket. Moreover, moisture sometimes enters between the meeting surfaces of the two members, developing 30 rust. Again, it sometimes happens that the inertia or momentum of the basket causes slipping upon the spindle when the spindle starts or stops too suddenly, and so impairs the surface of the spindle as to render it unfit for further use.

The present invention avoids the difficulties above enumerated by providing between the hub and the spindle a packing sleeve of metal relatively softer than that of the spindle or hub, and of such nature that when the 45 hub of the receptacle is driven on the spindle, the metal of the sleeve will conform to the surfaces and the space between the parts with such exactness as to produce a rust-proof joint, sheath the tapered end of the 50 spindle from any injury that might be imposed by sand or grit, and leave a relatively soft body in between the two members which can readily yield in the pulling operation and permit the parts to separate without in-

jury to either of the more expensive members, and by thus restricting any injury resulting either from operation or disassembling to the relatively inexpensive sleeve, effect a great saving in the use of this class of machines.

Preferably the top of the hub and spindle are extended above the high water level of the basket to prevent water reaching the joint between them, and as a further safeguard a cap overlies the joint and has a depending flange which surrounds the upper end of the hub as far down as the water line.

In the accompanying drawings—

Figure 1 is a vertical axial section of a centrifugal extractor embodying the several 70 features of the present invention.

Figure 2 is a detail view in axial section, and on an enlarged scale, of the parts with which the invention is particularly concerned; and

Figure 3 is a detail view of the end of the spindle, its hub, and the pulling yoke used for disassembling the parts.

1 represents the spindle and 2 the basket mounted on the upper end of said spindle in 80 a known type of centrifugal extractor. The member 2 is generally constructed with a cast metal hub 3, and the spindle 1 is provided with a tapered end to receive said hub.

According to the present invention the 85 bore of the hub 3 and the receiving end of the spindle 4 are tapered as heretofore, but the bore is of sufficiently greater diameter than the end of the spindle to admit a packing sleeve 5, which fits the tapered end of 90 the spindle and is itself provided with a tapered external surface fitting closely in the tapered bore of the hub 3. Preferably the same taper is used for the end 4 of the spindle 1 and the bore of the hub 3; that is to 95 say, the bore is tapered parallelly with the end of the spindle but of materially larger diameter so as to leave a substantial space in which the sleeve 5 fits, and of such form that it will receive a sleeve of uniform thickness 100 from end to end.

The sleeve 5 is made of some soft metal, such, for instance, as babbitt, and when the hub 3 is forced upon the seat provided by this sleeve around the tapered end 4, the 105 sleeve flows into such intimate contact with the two surfaces with which it lies as to make a rust-proof joint, besides protecting

the spindle, facilitating drawing the hub from the spindle, and realizing other advantages hereinbefore set forth.

Overlying the joint established by the sleeve 5 between the spindle end 4 and hub 3 is a cap 6 secured in place by screw 7. Hub 3 has an upward extension 3^a by which the upper end of the aforesaid joint is kept above the water line of the basket, and cap 6 has a depending flange 6^a which surrounds this upward projection of the hub and prevents access of the water to the joint.

For drawing the hub from the spindle, a yoke 8 may be used with lugs 9 fitting into the annular groove 10 of the upward extension of the hub, and with its screw 11 bearing upon the end of the spindle after the cap is removed.

I claim:

20 1. In a centrifugal machine, a vertical spindle of hard metal having an upwardly presented, longitudinally tapered free end, a packing sleeve of soft metal closely fitting said tapered end and having a longitudinally tapered outer surface, a basket having
25 a metal hub bored to closely fit the packing

sleeve and establishing frictional driving connection through said packing sleeve with the spindle, and a cap overlying the end of the joint formed by said packing sleeve between said spindle and hub, and having a depending flange surrounding the end of the hub. 30

2. In a centrifugal extractor, a vertical spindle having a longitudinally tapered free upper end, a basket having at the bottom thereof a hub constructed with a bore tapered substantially parallel with the taper of the spindle but of materially greater diameter, a packing sleeve of soft metal interposed between said spindle and hub, closely fitting both members and establishing frictional drive between them, and a cap overlying the end of the joint formed by said packing sleeve between said spindle and 40 hub, and having a depending flange surrounding the end of the hub and depending thereon to the upper water line of the basket. 45

Signed at Chicago, Illinois, this 7th day of Sept., 1920.

WILLIAM BARTHOLOMEW.
